Ms. 797

James Hartow and John Currie, of Philadelphia, Pa.
Assor. to Lovy, Hager and Lovy, of Philadelphia, (aforesaid)
Letters Patent No. 497, Dated May 27th 1856.

The Schedule referred to in these Letters Patent, and making
part of the same.

To all whom it may concern:

Be it known that we, James Hartow and
John Currie of the City and County of Philadelphia, and
State of Pennsylvania, have produced a new and original
design for Stoves known as Portable Ranges; And we do here-
by declare that the following is a full, clear and exact des-
cription of the said design; reference being had to the
annexed drawings forming part of this specification, in
which

Figure 1. is a front elevation of the stove.

Figure 2, is an elevation of end of stove, on left hand
looking to front.

Figure 3, is the panel on right hand end.

Similar letters of reference in the several figures denote the same part of stove and design.

The front plate A, bears over door B, raised panel C, feed door D, and draught door E. The top and bottom of this plate are ornamented by mouldings a and b, which joining with mouldings on edges of top plate F, and base plate G, constitute an ornamental base and cornice to the stove. This system of mouldings extends around the stove, and is made up as shown in the drawing. Above over door B, are the raised capitals and numerals "Pat'd 1836."

The over door B, is raised above the front plate by a moulding C, and bears in bas-relief a central sun d, and sweeping foliage e, arranged and configured as set forth in figure 1.

Panel C, is embellished by an ornament in bas-relief made up of spears f, foliage g, and band h, having the arrangement and configuration set forth in fig 1.

The feed door D, is ornamented by foliage i, sweeping from centre to ends, and the corners of the draught door bear foliage k; the arrangement and configuration of these ornaments being as shown in fig 1.

The end panels H and I, bear ornaments in bas-relief, composed of shield l, surmounted with foliage m, and having foliage n, on each side, sweeping gracefully from the bottom upward. The central figure p on panel H, is crossed by lines o: On panel I, this figure is plain. The configuration and arrangement of these ornaments are set forth in figs 2 & 3.

We claim as our production, the design, configuration, and arrangement, of the ornaments in bas-relief, and mouldings, as herein set forth, and shown in the annexed drawings; constituting a new and original stove design.

In testimony whereof, we have hereunto
